POCKET CASE

Max Kaplan, New York, N. Y.

Application November 8, 1946, Serial No. 708,588

19 Claims. (Cl. 206—41)

1

This invention relates to pocket cases, especially flat cases such as cigarette cases and vanity cases.

The primary object of the invention is to generally improve such pocket cases. They are often made with flexible, non-metallic coverings, such as fabric, leather, imitation leather, or the like. By stretching the flexible material taut over an annular or ring-like frame (which may be circular, square, rectangular, or elliptical, etc., in outline), the top and bottom of the case are given a relatively soft, yieldable surface which is pleasing to the touch.

One object of the present invention is to provide a sturdy, light weight frame for the pocket case, said frame being made of relatively thin sheet-metal parts. Still another object is to facilitate assembly of said parts during manufacture. Still another object is to provide a frame assembly having a finishing ring which is held in place solely by friction.

A further object of the invention is to provide a finishing ring which includes a narrow inside flange which bears against lining material inside the case, and which helps improve the interior appearance of the case, particularly when, as is preferably the case, the finishing ring is plated with a bright or precious metal. Still another object of the invention is to provide a finishing ring with an outside flange which is pressed flush against the covering material outside the frame, the flange of said finishing ring preferably presenting a color contrast on the outside of the case relative to the soft, flexible covering material, and preferably having a width sufficient to simulate the use of thick metal.

When the case is designed for cigarettes, the cigarettes are preferably held in position by means of elastic tapes. Some objects of the invention center about the attachment of the ends of the elastic tapes to the frame, and are to provide a neat, inconspicuous metal clip which securely anchors the end of the elastic; which is so shaped as to guard the same against excessive wear; which supports the elastic in elevated position; and which is readily secured to the frame without interfering with the assembly of the parts of the frame.

Further objects of the invention center about the lock for holding the case closed. The lock

2

here disclosed is of the slide type, and in accordance with the present invention the rail on which the slider moves is formed integrally with one finishing ring, and similarly, the lug or rib which is engaged by the slider is formed integrally with the other finishing ring, without necessitating soldering, brazing or the like.

To accomplish the foregoing general objects, and other more specific objects which will hereinafter appear, my invention resides in the pocket case elements, and their relation one to the other, as are hereinafter more particularly described in the following specification. The specification is accompanied by drawings, in which:

15 Fig. 1 is a plan view of an open cigarette case embodying features of my invention;

Fig. 2 is an elevation thereof;

16 Figs. 3, 4, 5, 6 and 7 are partially sectioned views showing the parts of one side or half of the case;

Fig. 8 is a fragmentary section drawn to enlarged scale, and taken through an edge of the case, for example, at the line 8—8 of Fig. 1;

20 Fig. 9 is a section through the edge of the case at the lock, taken approximately at the line 9—9 of Fig. 1, but with the case closed;

Fig. 10 is a front elevation of the slider of the lock;

25 Fig. 11 is a fragmentary section through an edge of the case at the elastic tape, for example at the line 11—11 of Fig. 1;

Fig. 12 is a perspective view of a metal clip used to hold the end of the elastic tape; and

30 Fig. 13 is a section through the case at the hinge, taken, for example, at the line 13—13 of Fig. 1, but with the case closed.

Referring to the drawing, and more particularly to Figs. 1 and 2, the pocket case is here exemplified by a cigarette case having two sides or 35 halves 12 and 14 hingedly connected at 16. The cigarette case is rectangular, but may be square, and it will be understood that if the pocket case is used for some other purpose, as, for example, for a loose powder compact, the case may be rectangular, square, circular or elliptical, etc.

With a cigarette case, the two sides 12 and 14 are substantially alike in depth, each receiving a layer of cigarettes, but it will be understood that with a vanity case the two sides may, if desired, differ substantially in depth, one side being rel-

atively deep, and the other relatively flat or shallow, and acting merely as a cover.

Referring now to Fig. 8, the case comprises a metal frame, and a flexible covering material 18 stretched taut by the frame. The specific frame here illustrated comprises three rings, namely a spreader ring 20 over which the covering material is stretched with its edge turned inwardly as shown at 21, a clamping ring 22 which is pressed frictionally inside the spreader ring 20, and a finishing ring having an inside wall 24 pressed frictionally within the clamping ring 22, and having a face wall 26 coming over the clamping ring.

A feature of the present invention is that the finishing ring has an outside flange 28 which is pressed flush against the covering material at 30 outside the spreader ring 20. The flange 28 presents a color contrast on the outside of the case relative to the covering material, particularly in view of the fact that the finishing ring is plated with a bright coating, preferably a precious metal such as silver or gold. The over-all appearance when the case is closed is somewhat as though the face wall 26 were made of thick metal, instead of being made of thin metal with a flange bent outwardly as shown.

The finishing ring is also preferably provided with an inside flange 32. This helps improve the appearance of the case when open. It also helps hold the lining material 34 in place, the latter usually being made of a suitable fabric, although thin leather or other material may be employed.

The parts which make up one side of the frame are shown separated in Figs. 3 through 7 of the drawings. The covering material 18 shown in Fig. 7 is preliminarily stretched taut around the spreader ring 20 of Fig. 6, with the aid of cement if desired. The clamping ring 22 of Fig. 5 is then forced into position, thereby anchoring the covering material in place. The lining material 34 of Fig. 4 may then be added, and if desired, may be cemented to the covering material 18. The rings 20 and 22 are completely concealed in the finished case, and require no polishing, plating, or other finish. The finishing ring is shown in Fig. 3, and this is given a high polish, and is preferably plated with precious metal. It is pressed into position, and is held frictionally. No special detents need be struck through the inside wall 24 (Fig. 8) of the finishing ring to hold the ring in position, and therefore the inside appearance of the case is unmarred. One of the advantages of making the clamping ring 22 U-shaped in cross-section, as is best shown in Fig. 8, is that it provides a resilient fit against the finishing ring, and so holds it effectively by friction alone.

The lock is a slide lock, and referring to Figs. 1 and 2, it comprises a slider 40 slideable on a rail 42 and having a detent lip 44 which cooperates with a lug or rib 46 on the other half of the case. The lock is shown in greater detail in Figs. 9 and 10, referring to which it will be seen that the metal of the finishing ring includes the inside flange 32, the inside wall 24 and the face wall 26 previously referred to, but the face wall is extended and folded sidewardly at 48, reversely at 50, and again reversely at 52, to form a rail which is symmetrical, and T-shaped in section. Beneath the rail 42 there is no outside flange (such as 28 in Fig. 8), but the absence of the outside flange is not conspicuous because of the overhang of the rail 42.

On the other half of the case, the finishing ring includes the inside flange 32, the inside wall 24,

the face wall 26, and the outside flange 28. At a portion of its free edge the latter is extended and turned upwardly to provide the rib 46 which is engaged by the detent lip 44 of slider 40, as is best shown in Fig. 9.

The slider itself is in the present case made of sheet metal, and is hollow. A piece of sheet metal is dished upwardly to form the handle portion of the slider. At the ends, the metal is turned outwardly, as indicated at 54 in Fig. 10. At the sides near each end, the metal is folded inwardly around the rail, as is indicated at 56 in Figs. 9 and 10. The detent lip 44 previously referred to is formed at the side of the slider between the inturned portions 56, this being best shown in Fig. 10. It will be understood that on the opposite side of the slider there is no need for a detent lip such as the lip 44, and none is provided.

The ends of the guide rail are so shaped as to stop the slider from sliding off the rail. In the present case the web of metal leading to the reversely folded top of the T is cut away near the ends of the rail, as is indicated at 58 in Fig. 10. The top of the rail is then bent downwardly or toward the casing, as shown at 60, thereby preventing escape of the slider.

If desired, the motion of the slider may be limited by additional means between a center position and one end position, in which case the rib 46 is sloped as shown at 62 in Fig. 1, at that end over which the slider moves.

Referring now to Fig. 1, the cigarettes are held in the case by elastic tapes 64 and 66. These are anchored at their ends by suitable metal clips secured to the frame. Such a clip is shown in perspective in Fig. 12, it being made of metal and comprising reversely folded walls 70 and 72 between which the end of the elastic tape is clamped. A pair of tongues 74 project from one of the walls, and are adapted to be received through mating slots in the frame of the cigarette case, following which they are bent outwardly to lie flush in the frame. The wall 70 is preferably the inside wall, and the tongues 74 preferably project from the inside wall so that any pressure exerted by the tongues tends to close the walls 70 and 72 together, and so prevents escape of the tape. Moreover, the tongues then prevent sideward movement of the tape relative to the clip. The inside wall 70 is preferably bent inwardly on a curve, as is indicated at 76. The elastic tape is thus bent around a broad, rounded surface, which minimizes wear of the elastic tape. The inside wall 70 preferably projects above the wall 72, thus elevating the tape.

Fig. 11 shows the relation of the parts at one side of the case, these parts including the covering material 18 stretched taut over spreader ring 20 and held in place by means of clamping ring 22. The walls 24 and 26 of the finishing ring also correspond to the parts previously mentioned in connection with Fig. 8. The elastic tape 64 is clamped between inside wall 70 and the outside wall 72 of the clip, the latter being secured in position by means of the tongues 74. The metal of the inside wall 24 is displaced inwardly to provide clearance for the tongues 74, so that the finishing ring can be slid into position just as though the tape clips had not been added. Actually, the indentations for the tongues 74 are localized outside the ends of the wall 72, so that the wall 72 lies flush against the inside wall 24 of the finishing ring. Fig. 11 differs from this slightly 75 for the sake of clarity in showing the parts. It

will be understood that the metal clips are preliminarily secured to the ends of precut short lengths of elastic tape, and that the tapes together with the clips are assembled with the finishing ring before the finishing ring is added to the frame of the case. The frame holds the tongues and tape tight.

In Fig. 1 it will be seen that the tapes are displaced, one being lower and the other higher, so that they miss each other when the case is closed. This permits them to be elevated, as shown in Fig. 11. That in turn facilitates insertion and removal of the cigarettes, and helps keep the case thin.

Fig. 13 shows the rim of the case at the hinge. Referring to Fig. 13, the face walls 26 of the finishing rings are extended outwardly for a short distance, and curved to cylindrical shape to provide hinge bearings 16. It will be understood that the hinge bearings on one side of the case fit between the hinge bearings on the other side of the case, as is most clearly seen in Fig. 1. A hinge pin 17 is passed through the successive hinge bearings in order to join the sides of the case.

It is believed that the construction and method of assembly of my improved pocket case, as well as the many advantages thereof, will be apparent from the foregoing detailed description. The finished pocket case is handsome in appearance because of the band of metal around the center of the periphery when the case is closed, this band of metal being of contrasting color relative to the outside of the case, and preferably being brightly finished with a plating of previous metal. When the case is opened, this finish is seen at all exposed parts of the finishing ring, while the other rings of the frame are wholly concealed. The frame is made of thin sheet metal which is readily worked, yet the resulting frame is sturdy because of the hollow, box-like shape of the frame, and the manner in which the parts are assembled together. The assembly is comparatively easy because the parts fit together with a frictional fit. In preferred form, the frame comprises three rings, one being a spreader ring about which the covering material is preliminarily stretched, another being a clamping ring which is pressed frictionally into the spreader ring in order to hold the material in place, and the third being a finishing ring which in preferred form includes an inside flange, an inside wall, a face wall, and an outside flange. A neat and effective sliding lock is provided at minimum cost, for none of the parts need be soldered or brazed. When the case is used as a cigarette case, elastic tapes may be provided which are secured in position in a neat and inconspicuous manner. In fact, the clips holding the elastic are concealed by the elastic itself. Wear of the elastic is minimized because of the curvature given the inside wall of the clip at the bend of the tape.

Although a rectangular shape is preferred for a cigarette case, when a vanity case is made, the shape may be square, circular, or elliptical. With a circular or elliptical shape, a slide lock such as is here shown may be employed, with this difference, however, that the rail and slider are preferably curved on an arc conforming to the shape of the case, and the same applies to the rib which is encompassed by the lip of the slider. It will also be understood that some of the features of the invention may be used without necessarily using all, one extreme example being that the elastic tape and clips holding the same, while use-

ful for a cigarette case, would not be useful for a vanity case.

It will be understood that while I have shown and described my invention in a preferred form, changes may be made without departing from the spirit of the invention as sought to be defined in the following claims.

I claim:

1. A pocket case having two hingedly related sides, at least one of said sides comprising a metal frame and flexible covering material stretched taut by said frame, said frame comprising three rings, namely, a spreader ring over which the covering material is stretched with the edges of said covering material turned inwardly about the spreader ring, a clamping ring pressed frictionally inside said spreader ring, to lock the covering material in position, and a finishing ring having an inside wall pressed frictionally radially inward of and against an exterior surface of the clamping ring and having a face wall coming over the clamping ring.
2. A pocket case having two hingedly related sides, each side comprising a metal frame and flexible covering material stretched taut by said frame, said frame comprising a concealed ring over which the covering material is stretched, with the edges of said covering material turned inwardly over the outside of the ring and then reversely inside the ring, and a finishing ring having an inside wall forced within the concealed ring, a face wall coming over the concealed ring and the reverse bend of the covering material, and an outside flange pressed flush against the covering material outside the concealed ring, the flange of said finishing ring being narrower than the aforesaid inwardly turned covering material at the periphery of the case but having a width sufficient to simulate the use of thick metal for the frame, the aforesaid face walls coming into face to face contact when the case is closed, and the outside flanges then being contiguous and presenting a color contrast to the covering material around the periphery of the case.
3. A pocket case having two hingedly related sides, at least one of said sides comprising a metal frame and flexible covering material stretched taut by said frame, said frame comprising a concealed ring over which the covering material is stretched with the edges of said covering material turned inwardly, and a finishing ring having an inside flange, an inside wall forced within the concealed ring, a face wall coming over the concealed ring, and an outside flange pressed flush against the covering material outside the concealed ring, and a lining material having its periphery disposed between the covering material and the aforesaid inside flange of the finishing ring.
4. A pocket case having two hingedly related sides, at least one of said sides comprising a metal frame and flexible covering material stretched taut by said frame, said frame comprising three rings, namely, a spreader ring over which the covering material is stretched with the edges of the covering material turned inwardly about the spreader ring, a clamping ring pressed inside the spreader ring to lock the covering material in position, and a finishing ring having an inside wall forced radially inward of and against an exterior surface of the clamping ring, a face wall coming over the clamping ring, and an outside flange pressed flush against the covering material outside the spreader ring.
5. A pocket case having two hingedly related

sides, each side comprising a metal frame and flexible covering material stretched taut by said frame, said frame comprising three rings, namely, a spreader ring over which the covering material is stretched with the edges of said covering material turned inwardly about the spreader ring, and then reversely inside the ring, a clamping ring pressed inside said spreader ring to lock the covering material in position, and a finishing ring having an inside wall forced radially inward of and against an exterior surface of the clamping ring, a face wall coming over the clamping ring and the reverse bend of the covering material, and an outside flange pressed flush against the covering material outside the spreader ring, the flange of said finishing ring being narrower than the aforesaid inwardly turned covering material at the periphery of the case but having a width sufficient to simulate the use of thick metal for the frame, the aforesaid face walls coming into face to face contact when the case is closed, and the outside flanges then being contiguous and presenting a color contrast to the covering material around the periphery of the case.

6. A pocket case having two hingedly related sides, at least one of said sides comprising a metal frame and flexible covering material stretched taut by said frame, said frame comprising three rings, namely, a spreader ring over which the covering material is stretched with the edges of said covering material turned inwardly about the spreader ring, a clamping ring pressed inside said spreader ring to lock the covering material in position, and a finishing ring having an inside flange, an inside wall forced radially inward of and against an exterior surface of the clamping ring, a face wall coming over the clamping ring, and an outside flange pressed flush against the covering material outside the spreader ring, and a lining material having its periphery disposed between the covering material and the aforesaid inside flange of the finishing ring.

7. A slide lock for a pocket case having hinged frames, one of said frames having an outward extension folded sidewardly, reversely and again reversely to provide a symmetrical T-section rail, a slider reciprocable on said rail, a detent depending from said slider, and a lug or rib on the other frame adapted to be engaged by said detent when the slider is moved to locking position, the ends of said rail being so shaped as to stop the slider from sliding off the rail.

8. A slide lock for a pocket case having hinged frames, one of said frames having an outward extension folded sidewardly, reversely, and again reversely to provide a symmetrical T-section rail, a hollow sheet metal slider reciprocable on said rail, a detent depending from one side of said slider, and a lug or rib on the other frame adapted to be engaged by said detent when the slider is moved to locking position, the ends of said rail being bent toward the case to stop the slider from sliding off the rail.

9. A cigarette case having two hingedly related sides, at least one side comprising a rectangular metal frame including a finishing ring having an inside wall, a flexible tape extending across the case to hold the cigarettes therein, the ends of said tape being anchored in position by metal clips, each clip comprising reversely folded walls between which the end of the tape is clamped, the inner of said reversely folded walls extending above the outer of said walls and having its free end bent inwardly in the direction of the tape

5 to minimize wear of the tape, and a pair of tongues projecting outwardly from the lateral edges of the inner wall and being received through mating slots in the inside wall of the aforesaid finishing ring.

10. A cigarette case having two hingedly related sides, each side comprising a rectangular metal frame and flexible covering material stretched taut by said frame, said frame comprising three rings, namely, a spreader ring over which the covering material is stretched with the edges of said covering material turned inwardly about the spreader ring, a clamping ring pressed inside said spreader ring to lock the covering material in position, and a finishing ring having an inside wall forced within the clamping ring, a face wall coming over the clamping ring, and an outside flange pressed flush against the covering material outside the spreader ring, a flexible tape extending across each side of the case to hold the cigarettes therein, the ends of said tapes being anchored in position by metal clips, each clip comprising reversely folded walls between which the end of the tape is clamped, and

25 a pair of tongues projecting outwardly from the inner wall and being received through mating slots in the inside wall of the aforesaid finishing ring, said tongues being held between said finishing ring and said clamping ring.

11. A pocket case having two hingedly related sides, each side comprising a metal frame, and flexible covering material stretched taut by said frame, said frame comprising a concealed ring over which the covering material is stretched with the edges of said covering material turned inwardly, and a finishing ring having an inside wall forced within the concealed ring, and a face wall coming over the concealed ring, and a slide lock for said case at a point opposite the hinge, the metal of the finishing ring on one side of the case having an outward extension which is folded sidewardly, reversely, and again reversely to provide a symmetrical T-section rail, a slider reciprocable on said rail, a detent depending from one side of said slider, the finishing ring of the other side of the case having an outward extension providing a rib adapted to be engaged by said detent when the slider is moved to locking position, the ends of said rail being so shaped as to stop the slider from sliding off the rail.

12. A pocket case having two hingedly related sides, each side comprising a metal frame and flexible covering material stretched taut by said frame, said frame comprising a concealed ring over which the covering material is stretched with the edges of said covering material turned inwardly, and a finishing ring having an inside wall forced within the concealed ring, a face wall coming over the concealed ring, and an outside flange pressed flush against the covering material outside the concealed ring, said outside flange having a width sufficient to simulate the use of thick metal for the frame, the metal of said finishing ring on one side of said case having an outward extension which is folded sidewardly, reversely, and again reversely to provide a symmetrical T-section rail, a slider reciprocable on said rail, a detent depending from one side of said slider, the finishing ring of the other side of the case having an outward extension providing a rib adapted to be engaged by said detent when the slider is moved to locking position, the ends of said rail being so shaped as to stop the slider from sliding off the rail.

13. A pocket case having two hingedly related

sides, each side comprising a metal frame and flexible covering material stretched taut by said frame, said frame comprising three rings, namely, a spreader ring over which the covering material is stretched with the edges of said covering material turned inwardly about the spreader ring, a clamping ring pressed inside said spreader ring to lock the covering material in position, and a finishing ring having an inside wall forced radially inward of and against an exterior surface of the clamping ring, a face wall coming over the clamping ring, and an outside flange pressed flush against the covering material outside the spreader ring, and a slide lock for said case at a point opposite the hinge, the metal of said finishing ring on one side of the case having an outward extension which is folded sidewardly, reversely, and again reversely to provide a symmetrical T-section rail, a slider reciprocable on said rail, a detent depending from one side of said slider, the finishing ring of the other side of the case having an outward extension providing a rib adapted to be engaged by said detent when the slider is moved to locking position, the ends of said rail being so shaped as to hold the slider against removal from the rail.

14. A pocket case having two hingedly related sides, at least one of said sides comprising a metal frame and flexible covering material stretched taut by said frame, said frame comprising a concealed ring having a surface wall, a bevel wall outside the surface wall, and an edge wall, said covering material being stretched over said surface, bevel and edge walls and then folded reversely inside the ring, and a finishing ring having an inside wall, a face wall and an outside flange, said face wall facing the other side of the case, and said inside wall and outside flange extending from the face wall away from the other side of the case, said inside wall being forced slidably in position inside the concealed ring with a friction fit and being unmarred by detents or the like, said face wall coming over the concealed ring and the reversely folded covering material, and said outside flange being pressed against the covering material outside the concealed ring, said flange presenting a band of color contrast relative to the covering material around the outside peripheral edge of the case.

15. A metal clip for holding the end of an elastic retaining tape used in a cigarette case having a frame, said clip comprising relatively flat reversely folded walls between which the end of the elastic tape is to be clamped, one of said walls extending beyond the other wall and having its free end bent away from the said shorter wall to minimize wear of the tape, and a pair of tongues formed integrally with and projecting from one of said walls in a direction opposite the direction of the bend of the free end of the longer wall and adapted to be received through mating slots in the frame of the cigarette case.

16. A metal clip for holding the end of an elastic retaining tape used in a cigarette case having a frame, said clip comprising reversely folded walls between which the end of the elastic tape is to be clamped, one of said walls extending beyond the other wall and having its free end bent away from the other or shorter wall to minimize wear of the tape, and a pair of tongues projecting from the lateral edges of the longer wall past the lateral edges of the shorter wall, and adapted to be received through mating slots in the frame of the cigarette case, whereby the tongues help hold the end of the tape in position in the clip.

17. A cigarette case having two hingedly related sides, each side comprising a rectangular metal frame including a finishing ring having an inside wall, a flexible tape extending across each side of the case to hold the cigarettes therein, the ends of said tapes being anchored in position by metal clips, each clip comprising relatively flat reversely folded walls between which the end of the tape is clamped, the inner of said reversely folded walls extending above the outer of said walls and above said finishing ring, and having its free end bent inwardly in the direction of the tape in order to minimize wear of the tape, and a pair of tongues projecting outwardly from the lateral edges of one of the said walls and passing through mating slots in the inside wall of the aforesaid finishing ring.

18. A pocket case having two sides, at least one side comprising a metal frame and flexible covering material stretched taut by said frame, said frame comprising three rings, namely, a spreader ring which is angle-shaped in cross-section in order to provide a surface wall and an edge wall which is substantially perpendicular to the surface wall, said covering material being stretched over said surface and edge walls of said spreader ring, with the edge of said covering material being turned reversely around the edge wall, a clamping ring which is U-shaped in section, said clamping ring being pressed into the spreader ring, with the outer wall of the U bearing against the reversely turned edge of the covering material and being collateral to the edge wall of the spreader ring, said clamping ring serving to lock the covering material in position, and a finishing ring which is generally angle-shaped in section to provide an inside wall and a face wall, and which has an outside flange turned outwardly from the edge of the face wall, said finishing ring having its inside wall forced radially inward of and against an exterior surface of the inner wall of the clamping ring and having its face wall coming over the clamping ring and over the folded edge of the covering material, said outside flange being pressed flush against the covering material outside the spreader ring.

19. A pocket case having two sides, at least one side comprising a metal frame and flexible covering material stretched taut by said frame, said frame comprising three rings, namely, a spreader ring which is angle-shaped in cross-section in order to provide a surface wall and an edge wall which is substantially perpendicular to the surface wall, said covering material being stretched over said surface and edge walls of said spreader ring, with the edge of said covering material being turned reversely around the edge wall, a clamping ring which is U-shaped in section, said clamping ring being pressed into the spreader ring, with the outer wall of the U bearing against the reversely turned edge of the covering material and being collateral to the edge wall of the spreader ring, said clamping ring serving to lock the covering material in position, and a finishing ring which is generally angle-shaped in section to provide an inside wall and a face wall, and which has an inside flange turned inwardly from the edge of the inside wall and an outside flange turned outwardly from the edge of the face wall, said finishing ring having its inside wall forced radially inward of and against an exterior surface of the inner wall of the clamping ring and having its face wall coming over the clamping ring and over the folded edge of the covering material, said outside flange being pressed flush

against the covering material outside the spreader ring, and there being lining material inside the covering material with the periphery of the lining material between the aforesaid inside flange and the covering material.
